UNITED STATES PATENT OFFICE.

JOHN V. HAGSTROM, OF HADLOCK, WASHINGTON.

VENTILATOR FOR FOOTWEAR.

1,259,229.

Specification of Letters Patent. Patented Mar. 12, 1918.

Application filed March 28, 1917. Serial No. 158,011.

To all whom it may concern:

Be it known that I, JOHN V. HAGSTROM, a citizen of the United States, residing at Hadlock, in the county of Jefferson and 5 State of Washington, have invented certain new and useful Improvements in Ventilators for Footwear, of which the following is a specification.

This invention relates to boots or shoes, 10 and particularly to ventilating means therefor.

The object of the invention primarily is to provide improvements in means for introducing air to the foot portion of a boot or 15 shoe, so as to render the foot wear more comfortable, and to obviate foot soreness. A further object of the invention is to provide ventilating means for use in connection with boots or shoes, which will not create discom- 20 fiture to the wearer of the boot or shoe, and which will not detract from the appearance of the foot wear. A still further object is to provide a ventilating attachment for foot wear which is arranged in such man- 25 ner that the movements of the foot within the shoe will operate to introduce to or ex- pel air from the interior of the boot or shoe.

A still further and particular object of the invention is to provide a ventilating attach- 30 ment of the character set forth, which is ex- tremely simple and inexpensive of construction, which is capable of being readily applied to a boot or shoe without appreciably departing from the present construction of 35 the foot wear, and which will prove thoroughly efficient in attaining the ends set forth.

With these objects in view, together with others which will appear as the description 40 proceeds, the invention resides in the novel formation, combination, and arrangement of parts, all as will be described more fully hereinafter, illustrated in the drawings, and particularly pointed out in the claim.

45 In the drawings:—

Figure 1 is a side elevation of a boot, illustrating the application of a ventilating device constructed in accordance with the invention;

50 Fig. 2 is a vertical sectional view taken through the foot and upper portions of the boot; and

Fig. 3 is a transverse sectional view taken on line 3—3 of Fig. 1.

55 Referring to the drawings, 5 indicates the

foot portion of the boot, and 6 the upper thereof. The invention in the present instance is illustrated and described as being used in connection with rubber boots, but it will be understood that the invention is not 60 restricted to foot wear of this particular type and may be employed with equal efficiency in connection with foot wear of varied sizes, types, and designs.

The boot upper is provided preferably in 65 one side with an outwardly depressed por- tion indicated generally at 7. This de- pressed portion extends from the upper edge of the boot upper to the foot portion of the boot, and is of narrow width and shallow 70 depth. Arranged within this depressed portion is a ventilating tube 8. This tube may be formed of rubber, rubberized cloth, or any other suitable material, preferably, however, a material which will be flexible, 75 and water and air tight. The tube fits snugly within the recess formed by the out- wardly depressed portion 7 and communi- 80 cates at its upper end with the atmosphere and at its lower end with the interior of the boot and preferably adjacent the instep or heel portions thereof. It will also be observed that the lower end of the ventilating tube terminates slightly above the sole of the foot 85 wear.

In order that a ventilating device of this character will not cause discomfiture to the wearer, the tube is positioned between the boot upper and the lining therefor. The lining is indicated at 9, and the pliability of 90 the tube 8 permits the lining to lie smoothly against the interior surface of the boot upper so as to not bulge or break the smooth continuity thereof.

The lower end of the ventilating tube 95 communicates with the interior of the boot, as has been before stated, adjacent the heel or arch portions of the foot. It is well known that in walking these portions of the foot move appreciably within the shoe. 100 Such movements of the heel and arch por- tion of the foot obviously create movements in the air present in the shoe, and by so lo- cating the inner or lower end of the ventilat- ing tube, the disturbance of the air within 105 the shoe is transmitted to the air in the ven- tilating tube. The particular arrangement creates a constant inward and outward movement of air within the tube 8 when the foot is being moved, and therefore the inte- 110

rior of the foot wear is perfectly ventilated. By so constructing the boot, diseases of the feet will be overcome.

While the present is a disclosure of what I believe to be the preferred embodiment of the invention, it is to be understood that the invention is not limited thereto, but that various changes may be made in the construction, arrangement, and proportion of parts, without departing from the spirit of the invention, as defined in the appended claim.

What is claimed is:—

In a boot, outwardly pressed portions in the upper of said boot extending straight from the bottom to the top thereof and being located directly opposite to each other and a tube arranged within each of said out-

wardly pressed portions and between the said upper and the lining of the boot, the inner end of said tube communicating with the interior of the boot above the sole thereof and substantially midway between the rear of the heel and the arch of the boot, and the said tubes being oval in cross section so as to be wholly confined within the space provided by said outwardly pressed portions.

In testimony whereof I affix my signature in presence of two witnesses.

JOHN V. HAGSTROM.
